UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

BLANK-FEEDING DEVICE FOR MULTIPLE AUTOMATIC FOLDING MACHINES.

Original application filed September 10, 1921, Serial No. 499,614. Divided and this application filed November 23, 1923. Serial No. 676,569.

This invention relates more particularly to an improved type of sundae dish blank feeding mechanism, and is a division of my co-pending application for patent for a "multiple automatic folding machine", filed September 10th, 1921, Serial Number 499,614.

It is an object of this invention to provide a dish forming machine with an improved attachment operable from the machine and adapted to automatically feed sundae dish blanks into the machine one at a time to be formed into sundae dishes.

It is also an object of the invention to provide a dish forming machine with a blank feeding mechanism operable by a mutilated gear mechanism for removing prepared blanks singly from a blank holding magazine.

It is a further object of this invention to provide a forming machine with a blank feed mechanism including a magazine and intermittently operated means for removing blanks from the magazine one at a time by a slight buckling movement.

It is furthermore an object of the invention to provide a blank feeding mechanism for a dish forming machine, said mechanism having a manually adjustable clutch means for timing the feeding mechanism.

It is an important object of this invention to provide a dish forming machine with a blank feeding attachment of improved and simplified construction adapted to be properly timed to buckle and remove blanks one at a time from a magazine and feed the same into the field of operation of the forming mechanisms of the machine.

Other and further important objects of this invention will be apparent from the disclosures in the specification and the accompanying drawings.

The invention, in a preferred form, is illustrated in the drawings and hereinafter more fully described.

On the drawings:

Figure 1 is a top plan view of a sundae dish forming machine equipped with a blank feeding mechanism embodying the principles of this invention.

Figure 2 is an enlarged front elevation of the blank feeding mechanism.

Figure 3 is a reduced view taken on line 3-3 of Figure 2.

Figure 4 is a sectional view taken on line 55 4-4 of Figure 3.

As shown on the drawings:

The reference numeral 1 indicates a pulley adapted to be driven by any convenient source of power to cause operation of the machine. The pulley is mounted to rotate on a shaft supported on the machine frame 2 and is adapted to transmit a drive through suitable gearing to a gear 3 which drives a shaft 4 through a clutch mechanism 5. A gear on the shaft 4 to the inside of the frame 2 meshes with a gear 6 to cause operation of a disk 7 connected to operate a Geneva gear 8. The Geneva gear 8 is mounted to operate the meshing gears 9 and 10 and thus transmits a drive to a shaft 11 which is connected by beveled gears 12 and 13 to operate the dish forming mechanism denoted as a whole by the reference numeral 14.

Mounted on the shaft 4 is a beveled gear 15 which meshes with a beveled gear 16 mounted on a shaft 17 which drives the feeding means which delivers the blanks to the forming mechanism. As shown in Figure 3 the shaft 17 extends to the forward part of the machine through a bearing sleeve 18 mounted on the front plate or bracket member 19 of the machine. Keyed on the outer end of the shaft 17 is a pinion 20 in mesh with a gear 21. The gear 21 in turn drives a smaller gear 22 mounted on a shaft 23. Adjustably mounted on the outer end of the shaft 23 is a pair of mutilated gears 24 and 25 adapted to cooperate with two corresponding mutilated gears 26 and 27 respectively which drive the blank feeding rollers. An adjustable clutch member 30 is provided on the shaft 23 which is operated by a knurled knob 31 so that the relative position of the mutilated gears 24 and 25 may be adjusted as desired with respect to their respective feed roller gears 26 and 27. Each feed roller comprises a plurality of disks 28 separated by diametric ribs 29 having two diagonally opposite corners projecting slightly beyond the periphery of the disks 28. The ribs 29 are covered with friction strips 32 made of rubber or other suitable material. The friction portions extend around only a portion of the periphery of the rollers so as to operate upon paper blanks which are to be

100
105

fed only at predetermined times to the forming mechanism of the machine.

Mounted above the blank feed rollers is a magazine comprising a circular base section 33 provided with uprights 34 for holding a plurality of superimposed prepared dish blanks 35. Keyed upon the shaft 17 adjacent the bevel gear 16 is a sprocket wheel 36 having a chain 37 thereon which drives a corresponding sprocket wheel 38 keyed to a shaft 39 on the inner end of which is mounted a driving gear 40. The driving gear 40 is in mesh with a corresponding gear 41 which in turn drives a similar gear 42 connected to auxiliary advancing rollers 43 and 44 for the paper blanks. The upper auxiliary roller 44 is movably supported, being positioned in pivoted bearing members 45 which are held in lowered position by means of coiled springs 46 as best shown in Figure 2. The upper ends of the springs 46 are attached to the ends of a rod 58 connecting the pivoted members 45. The lower ends of the springs 46 are secured to the machine frame. A cam 47 is mounted on the shaft 23 (Figure 4) and is adapted to cooperate with a lever 48 pivoted at 49 on a bracket secured to the machine frame. A roller 50 is supported on one end of the lever 48 and rolls on the periphery of the cam 47. The opposite end of the lever 48 is pivoted to a short link 51 connected in turn to a bell-crank lever 52 which is pivotally mounted on the frame of the machine by being keyed to a shaft 53. The upper end of the bell-crank lever 52 is formed in the shape of a finger 54 adapted to operate as a pusher member. A duplicate finger 54 is provided on the other end of the shaft 53 to properly advance the prepared paper blank toward the forming mechanism after it has been fed forwardly by the feeding means described. The pusher fingers 54 are operated simultaneously by the rotation of the shaft 53 which extends across the machine in suitable brackets 55 provided therefor beneath a feed table 56. The ends of the fingers 54 project upwardly through slits 57 provided in the table 56.

The operation is as follows:

The machine is set in operation by the revolution of the pulley 1 driven from any suitable source of power. The clutch 5 is then actuated or set to cause the drive from the pulley 1 to be transmitted to the dish forming mechanism 14 and the dish blank feeding mechanism of this invention. The shaft 4 is driven through the clutch connection and with it the bevel gear 15 is rotated to revolve the bevel gear 16 to drive the feeding mechanism which serves to continuously deliver prepared dish blanks 35 to the forming device.

The delivery of the blanks is accom-

plished by means of the feed rollers having the rubber friction strips or pads 32 on the portions 29 and actuated by the mutilated gears 24 and 25 cooperating with the mutilated gears 26 and 27 which drive the feed rollers 28. It will be seen that if the first feed roller, at the left of Figure 4, is rotated slightly in advance of the second feed roller that the lowermost blank 35 in the magazine 33 will be slightly buckled on account of the earlier movement of the friction members 32 on the first feed roller. The lowermost blank is thus separated from the remaining blanks in the magazine. The blank having been properly separated or buckled, the two feed rollers 28 are rotated in unison by means of their operating mutilated gears 26 and 27 and act to feed the blank forward out of the magazine to the auxiliary feed rolls 43 and 44 which if desired, may be slightly separated at this time by means of a cam action (not shown). The auxiliary rolls 43 and 44 are normally held in co-acting position by means of the coiled springs 46. The auxiliary feed rolls 43 and 44 are driven by means of the chain 37 on the sprocket wheels 36 and 38 cooperating with the gears 40, 41 and 42, and feed the blank forwardly over the top of the table 56. At the same time the cam 47 has acted to retract the pusher fingers 54 in the table slots 57 and after the blank has been pushed forward sufficiently by means of the auxiliary rolls 43 and 44 the pusher fingers 54 are actuated by the cam 47 to push the advanced blank forwardly a slight additional distance into proper position on the table 56 in the field of operation of the dish forming mechanism 14 to be formed into a sundae dish.

I am aware that numerous details of construction may be varied through a wide range without departing from the principles of this invention, and I therefore do not purpose limiting the patent granted otherwise than necessitated by the prior art.

I claim as my invention:

1. In a machine for automatically forming receptacles the combination of a blank feeding means, said feeding means including a magazine, intermittently operated means for removing blanks singly from the magazine, a mutilated gear mechanism for operating said feeding means, a clutch device for adjusting the mutilated gear mechanism, and a manually adjustable shaft supporting said clutch device.

2. In a machine for automatically forming receptacles the combination with a blank feeding means including a magazine and intermittently operated means for removing blanks singly from the magazine, said intermittently operated means including devices for automatically separating the lowermost blank from its adjacent blank by a slight

- buckling movement of the lowermost blank, and manually adjustable mutilated gear mechanisms for operating the feeding means.
- 6 3. In a machine for automatically forming receptacles the combination of a blank feeding means including a magazine and intermittently operated means for removing blanks singly from the magazine, said intermittently operated means including devices for automatically separating the lowermost blank from its adjacent blank by a slight buckling movement of the lowermost blank, mutilated gears for driving the feed means to accomplish said buckling movement, and manually adjustable mutilated gears for actuating said first mentioned mutilated gears.
- 10 4. In a machine for automatically forming receptacles the combination with a blank feeding means, including a magazine and intermittently operated means for removing blanks singly from the magazine, said intermittently operated means including mutilated gears for operating devices for automatically separating the lowermost blank from its adjacent blank, and a manually adjustable clutch means for timing said feeding means.
- 15 5. In a machine for automatically forming receptacles the combination with a blank feeding means, manually adjustable mechanisms for adjusting and timing the feeding means, said feeding means including a magazine and intermittently operated means for removing blanks singly from the magazine, said means including devices for automatically separating the lowermost blank from its adjacent blank by a slight buckling movement of the lowermost blank, said buckling means including feed rollers having friction faces and mutilated gears thereon, one of said rollers adapted to operate while the other roller remains stationary.
- 20 6. In a machine for automatically forming receptacles, the combination with a blank holding magazine, intermittently operated rollers for removing blanks from the magazine, friction portions on said rollers for automatically separating the lowermost blank from an adjacent blank, mutilated gears on said rollers, adjustable mutilated gears co-acting therewith, and means for adjusting the relative position of the adjustable mutilated gears with respect to the mutilated gears on said rollers.
- 25 7. In a receptacle forming machine, the combination with a blank holding magazine, intermittently operated rollers for removing a blank from the magazine, friction portions on said rollers for buckling the blank, mutilated gears on said rollers, a shaft, means for operating the same, adjustable mutilated gears on said shaft for co-action with the roller mutilated gears, and a clutch mecha-
- nism on said shaft for adjusting the relative position of the adjustable mutilated gears with respect to the roller mutilated gears.
8. In a receptacle forming machine the combination with a blank holding magazine of intermittently operated rollers for removing a blank from the magazine, mutilated gears on said rollers, adjustable mutilated gears for co-action therewith, and means for adjusting the adjustable mutilated gears with respect to the mutilated gears on said rollers.
- 10 9. In a receptacle forming machine the combination with a blank holding magazine, of intermittently operated rollers, means thereon for buckling a blank and removing the same from the magazine, mutilated gears on said rollers, adjustable mutilated gears for co-action therewith, and a manually operable clutch mechanism for adjusting said adjustable mutilated gears with respect to the mutilated gears on said rollers.
- 15 10. In a receptacle forming machine the combination with a blank holding magazine, of intermittently operated main rollers for buckling a blank and removing the same from the magazine, a gear mechanism for actuating said rollers, a table, and auxiliary rollers between the table and said magazine adapted to be operated from said gear mechanism to advance the blank onto the table.
- 20 11. In a receptacle forming machine the combination with a blank holding magazine, of intermittently operated main rollers for buckling a blank and removing the same from the magazine, a gear mechanism for actuating said rollers, a table, auxiliary rollers operated from said gear mechanism to advance the blank onto the table, pusher members, and means operated from said gear mechanism for actuating the pusher members at predetermined times to cause the blank to be pushed into a predetermined position on said table.
- 25 12. In a receptacle forming machine the combination with a blank holding magazine, of main rollers for buckling a blank and removing the same from the magazine, a gear mechanism for actuating said rollers, a table having openings therein, auxiliary rollers operated from said gear mechanism to advance the blank onto the table, pusher members adapted to be projected through the table openings, links connected with said pusher members, a lever for rocking said links, and a cam operated from said gear mechanism for actuating the lever at predetermined times to cause the pusher member to push the blank into a predetermined position on the table.
- 30 13. In a receptacle blank feeding mechanism, a magazine for holding a stack of blanks, and rollers operable at different times for first buckling and then removing blanks singly from the magazine, each of

said rollers comprising a plurality of spaced disks separated by diametrical portions having diagonal corners projecting beyond the periphery of said disks, and strips of material engaged around said diametrical portions.

14. In a receptacle blank feeding mechanism, a magazine for holding blanks, main

rollers for first buckling and then advancing a blank from the magazine, auxiliary ¹⁰ rollers for continuing the advance of the blank, and pushers for still further advancing the blank.

In testimony whereof I have hereunto subscribed my name.

CESARE BARBIERI.
